EMILE DREYFUS-ROSE, SAID ROSE AND VICTOR ROCH VAISSET, OF PARIS, FRANCE

STRUCTURE AND STRUCTURAL BLOCK

Application filed February 17, 1932, Serial No. 593,616, and in Belgium March 25, 1931.

The present invention relates to structures and structural blocks.

One of the objects of the invention is to provide a structural block formed of brick, cement, terra cotta or the like and so shaped at its extremities that it limits together with an adjacent block of identical or similar structure a chamber into which cement or other binding materials may be poured.

Another object is to provide a form of building block having extremities shaped so that, when pushed into contact with an upright of any kind, the block comes automatically into alignment with those below it.

The upright may be a structural steel beam, one formed in cement or simply the reinforcing rods traversing or intended to traverse the latter.

A further object is to provide a form of block in which the end surface is formed to permit a small amount of play for the purpose of aligning the block relatively to those beside and below it.

Another object still is to provide a structural assembly adapted to coact with blocks of the type above described so as to diminish the compressive load on the latter.

Still further objects will appear in the course of the detailed description now to be given with reference to the accompanying drawings, in which:

Figure 1 is a horizontal section through one form of block assembly;

Figure 2 represents a variant of the assembly shown in Figure 1, an auxiliary locking block being employed;

Figure 3 illustrates a third form of assembly utilizing blocks of the type shown in Figure 1 with an auxiliary block interposed, anteriorly, therebetween;

Figure 4 shows a form of assembly in which auxiliary blocks are interposed both anteriorly and posteriorly between adjacent principal blocks;

Figure 5 is a longitudinal section through a form of block fitted with a reinforcing element;

Figures 6 and 7 show variants of the form of assemblies illustrated in Figures 2 and 3 respectively;

Figure 8 is a section through a variant of the assemblies shown in Figures 1 and 4;

Figure 9 represents, in perspective, a structural assembly adapted to coact with blocks of the type shown in the preceding figures to diminish the compressive load thereon.

Referring to Figure 1 of the drawings, there is shown a building block *a* formed with appropriate interior heat insulating spaces and terminating at one or both extremities in a recessed portion *b* adjacent the anterior portion thereof, a prolongation *d* being formed at the posterior portion of the end surface, said prolongation having a small recessed portion *b'* formed therein.

From the foregoing, it will be readily seen that, when a brick is placed in contact with some such upright structural element as T-section beam *c* so that posterior prolongation *d* contacts with the posterior surface of the latter, brick *a* comes into alignment with similar bricks placed thereunder. At the same time, recessed surface *b* of adjacent blocks form a chamber into which cement or any binding material may be poured for the purpose of locking adjacent blocks to element *c* and to one another. By pouring cement or like binding material into the chamber limited laterally by recessed surfaces *b'*, a direct bond between adjacent blocks is established.

In the form of blocks represented in Figure 2, prolongations *d* of the type shown in Figure 1 are omitted and replaced by a locking or key block *g* terminating at each end in pointed ribs *g'* (round "ribs" of the type shown at *g'* in Figure 4 may be used instead of the pointed ribs shown to procure a locking action), cement mortar or the like being interposed between elements *g* and *a* to form a bond.

The form of block assembly illustrated in Figure 3 differs from the one shown in Figure 1 only in the addition of an anterior locking or key block *h* which may be placed in position prior to the pouring of cement or the like into contact with recesses *b*, said key block serving to fill the anterior space between adjacent blocks *a* and to hide the cement joint just behind.

In Figure 4, both anterior and posterior key blocks *g* and *h* are provided and combine the advantages and functions of like elements represented in Figures 2 and 3. While 5 blocks *g* and *h* are here shown with rounded lateral surfaces, the latter may be pointed as in Figures 2 and 3 or may take any other form insuring a proper locking action. It will be noted that blocks *a*, shown in this 10 figure lack prolongations of the type *d* shown in Figure 1 and conform approximately with those of the type illustrated in Figure 2.

Any one of the types of blocks illustrated in Figs. 1 to 4 inclusive may be fitted with 15 reinforcing metallic or similar rods *j* (Fig. 5) extending beyond the end extremities thereof and serving to lock the blocks in the cement or other binding material poured therebetween.

20 If the block is intended to form a corner, elements of the type of *a'* in Figure 1 should be used, one extremity being formed to coact with a similar extremity of block *a* and the other being shaped to fit into jointed relation with bricks or blocks of any desired 25 special shape.

It will be observed that, when anterior key 30 blocks of the type of elements *h* shown in Figures 3 and 4 are used, the latter serve to align the anterior surfaces of adjacent blocks. This form of assembly is particularly advantageous where uprights of the type of element *c* are lacking between adjacent blocks. 35 It is to be noted that elements *g* (Figures 2 and 4) may be used to perform a function similar to blocks *h*.

The form of assembly shown in Figure 6 40 illustrates a form of block *a* having a small posterior prolongation *d'* adapted to be used for aligning and also having a recess formed therein posterior to prolongation *d'* adapted to receive either cement (right hand side) or a locking key *g* having a lateral rib *g'* formed thereon of the types shown in Figures 2 and 4 (left hand side). If resistance 45 calculations or other considerations make it desirable to have an anterior cement prolongation *i* formed between blocks *a*, the latter may be formed by any suitable form of 50 mould.

The assembly shown in Figure 7 shows a 55 form of block similar to the one represented in Figure 3 coupled to a block of the type illustrated in Figure 1, an interior cement prolongation *i* being interposed therebetween. This figure is intended merely to illustrate the idea that blocks of the type shown in any single figure may be used in coaction with blocks of a type shown in some 60 other figure if desired.

Figure 8 shows another possible combination of blocks of different types, the right hand block being similar to the one in Figure 1 and the left hand block similar to the 65 one represented in Figure 4, the space be-

tween the two being filled with binding material.

Figure 9 represents a structural skeleton 70 designed to diminish the compression of blocks in superposed rows. Element *k* is a beam extending between adjacent uprights *c* and supporting cross beams *l*, blocks *m* being interposed in the space between blocks *a* and cross beams *l*. Beams *k* and *l* and even upright *c* may be formed of reinforced concrete 75 or any structural shapes of current design. An inspection of the drawings will at once show that elements *k* and *l* will act to take up the compressive effect of supposed rows of blocks.

Whatever be the form of block employed, 80 it is advisable to form the intersection between surfaces *b* and the internal surface of prolongations *d* curvilinearly so that when blocks *a* are pushed into contact with upright *c*, adjustment of the alignment of block *a* may be effected by varying the point of contact between said uprights and said curvilinear surface.

The invention is not to be taken as limited 85 to the particular structures shown in the drawings. If, for example, blocks *a* be laid in inclined tiers, their end surfaces may be modified in shape to permit their being laid in the manner described for horizontally 90 laid blocks.

It will be noted that blocks of the type 95 shown in Fig. 1 have ends of approximately L shape. This permits their being pushed laterally into contact with some such guides as elements *c*. This is of special importance 100 in practice since it permits placing the blocks in position when no free end space is available.

What we claim is:—

1. A supporting wall adapted to carry 110 heavy loads comprising a frame work including spaced upright supporting members comprising structural shapes, and vertically superposed blocks each supported by the lower blocks filling the space between the said uprights, each of said blocks being in substantially contact with the next lower block throughout the transverse dimension of the wall, each block extending horizontally substantially the full distance between two adjacent uprights and overlapping said uprights, the ends of said blocks being so shaped that they cooperate to form pockets for receiving the uprights, such pockets being substantially closed on three sides and being substantially open on the fourth side, the opening on such fourth side being wider than the width of an upright, whereby said blocks may be arranged in place by simple horizontal movement after the uprights have been put in place to form the frame.

2. In a wall according to claim 1, said blocks having symmetrical extensions on the ends thereof formed as prolongations of one 130

of the vertical faces, such prolongations co-operating to close one of the sides of the said pocket.

3. In a wall according to claim 1, such pocket having a greater width at an intermediate point than the width of said opening, and a plastic material filling the portion of said pocket not occupied by said upright, whereby said upright is locked in the pocket.

10 4. In a wall according to claim 1, said blocks having symmetrical extensions on the ends thereof formed as prolongations of one of the vertical faces, such prolongations co-operating to close one of the sides of the 15 said pocket, the adjacent faces of said pockets having opposed recesses therein, and a plastic material filling such recesses.

In testimony whereof we affix our signatures.

20 EMILE DREYFUS-ROSE SAID ROSE.
VICTOR ROCH VAISSET.
